UNITED STATES PATENT OFFICE.

ERNEST B. THURSTON, OF TOLEDO, OHIO, ASSIGNOR TO THE HAUGHTON ELEVATOR & MACHINE CO., OF TOLEDO, OHIO, A CORPORATION OF OHIO.

SWITCH MECHANISM.

Application filed July 13, 1921. Serial No. 484,429.

This invention relates to electromagnetic motor operated switches.

This invention has especial utility when incorporated in connection with polyphase electric current torque or high internal resistance switch operating motors for elevator service.

Referring to the drawings:

Fig. 1 is a wiring diagram wherein the alternating current is three phase three wire, incorporated for elevator service, with the controller on the elevator car, disclosing an embodiment of the invention;

Fig. 2 is a front elevation of the switch board for the wiring installation of Fig. 1;

Fig. 3 is a detail view of a flexible coupling;

Fig. 4 is a cross section of the accelerator switch cam shaft showing the general relation of the three cams thereon;

Fig. 5 is a detail view of the stop carrying bracket for the weights;

Fig. 6 is a side elevation of the main motor switch cam, contact carrying arm, and cam engaging means;

Fig. 7 is a section of the direction switch rock shaft with arm for picking up the weights; and

Fig. 8 is a view of the direction switch actuating cams.

In the elevator shaft 1 having landings 2 is operable elevator car 3 carried by hoist line 4 passing about drum 5 over idler 6 to counterweight 7. Alternating electric current supply is shown which may be sixty cycle, three phase, by way of supply lines 8, 9, 10. From the line 8 branch line 11 extends past upper overtravel switch 12, thence by line 13 past lower overtravel switch 14, thence by line 15 past emergency switch 16 in the car 3, thence by line 17 past lower final or stopping switch 18 by way of line 19 to contact 20 on arm of controller 21 in the car 3. This contact 20 on the controller 21

when in off position connects across to line 21' past upper final or stopping switch 22 thence by line 23 to connect with the line 17. The emergency switch 16 is accordingly in the lines for both overtravel limit switches as to the supply from the line 8. From the supply line 10 is branch line 24 past upper overtravel switch 12, thence by way of line

25 past the lower overtravel switch 14, thence by line 26 past the lower or final or stopping switch 18, and thence by way of line 27 to controller carried bottom contact 28 on the controller 21. Should this lower final or stopping switch 18 be open, there is branch line 29 from the line 26 by way of the upper stopping switch 22 extending from thence by line 30 to the lower contact 28 of the controller 21. Accordingly, in shifting the controller 21 to the left, the contact 20 is moved away from the line 21' and the contact 28 is moved away from the line 30. This automatically cuts out the upper final switch 22 as to the controller 21, for this shifting of the controller to the left is effective for operating the car 3 for downward travel. Reverse shifting for car travel upward cuts out the switch 18.

The contact 20 is in this movement brought to connect the line 19 with line 32 extending to line 33. Simultaneously with this shifting of the contact 20 of the controller 21, the contact 28 of the controller 21 connects the line 27 with line 34. These lines 33, 34, extend to main switch operating motor 35, the third line to this motor being connected by way of line 36 to line 37, contact 38 on the accelerating switch, and thence by line 39 to line 40 connecting with the supply line 9. This main switch motor 35 has shaft 41 provided with flexible connection 42 to rock shaft 43 carrying cam 44 effective for throwing switch contacts 45, 46, of the main switch.

Further shifting of this controller 21 in the car 3 to the left brings the contact 20 to line 47 extending to line 48, while simultaneously the contact 28 is swung to line 50. These lines 48, 50, extend to direction switch operating motor 51 having a third line 52 therefrom connected with the line 40 from the supply line 9.

This energizing of direction switch torque motor 51 operates its motor shaft 53 having flexible coupling 54 with rock shaft 55 carrying direction switch operating cams 56, 57. The cam 56 for down direction travel of the car 3 throws contacts 58, 59. The contact 59 is effective by way of line 60 from the supply line 10 by the main motor switch contact 46 to line 61. Simultaneously the sup-

- ply line 8 is connected by contact 58 with line 62. The throw of the main switch contact 45 connects supply line 9 with line 63. These lines 61, 62, 63, extend to three phase slip ring main elevator motor 64. From the line 62 extends the line 65 to coil 66, thence by line 67 to line 63. Accordingly, simultaneously with the energizing of the field coil from the lines 61, 62, 63, of this motor 64, coil 66 releases brake 68 so that this motor 64 may operate shaft 69, and through worm speed reduction gearing 70 rotate the drum 5 in a direction to lower the car 3 in the shaft 1.
- 13 The line 61 has branch 71; the line 62, branch 72, extending to accelerator switch motor 73 having a third line 74 therefrom connected to line 63. The accelerator switch torque motor 73 is on shaft 75 having pinion 76 in mesh with gear 77 for two to one speed reduction driving of cam shaft 78 carrying cams 79, 80, 81. The travel of this cam shaft 78 is resisted. This resistance is herein shown to embody a disk 82 having flexible connection 83 with piston 84 in cylinder 85 as a dash pot device, the leakage of which may be adjusted by valve 86. Accordingly, the main switch operating torque motor 35 is first effective, and as the controller 21 is shifted to the second position, the direction switch torque motor 51 becomes effective. Simultaneously with the operation of this direction switch motor 51, accelerating switch motor 73 is actuated. As the shaft 78, retarded by the dash pot device 82, 83, 84, 85, 86, starts operation there is a throwing of contact 87 for cutting out the first portion of starting resistance 88 in the main motor 64. At the determined period of time thereafter in the operation of the shaft 78, contact 89 cuts out an additional portion of the resistance 88 and this is followed by contact 90 cutting out the balance of the resistance 88 as the motor 64 thus comes up to speed.
- 45 The movement of the contact 87 carries with it the contact 38, thereby opening the line initially effective for completing the plurality of phases for operating the main switch motor 35. However, inasmuch as the main switch is thrown, the contact 45 carries with it contact 91 maintaining closed the circuit between lines 37, 40, so that the action of the accelerating switch does not effect an opening of the main switch. The main motor 64 may accordingly be stopped by cutting out the direction switch short of coming to neutral position to cut out the direction motor 51 and the main switch will still be held in. However, any other action of the controller, or action as to the lines which cuts out the main switch at once brings about a full stopping of the main motor 64 and there may not be a restarting of this main motor 64 until after the accelerating switch has come to starting position.
- For upward direction of travel, the controller 21 is shifted to the right for direction switch contact 20 engaging with line 33, and contact 28 with line 92, the latter extending to line 34. Further shifting of this controller 21 for effecting upward direction travel brings the contact 20 to line 49 and the contact 28 to the line 48, reversing the throw operation of the motor 51.
- The embodiment of the devices of this disclosure for electromagnetic or torque motor control for all of the switches is herein developed for a main assembly control board embodiment in the remote control of the switches from the elevator car. Control board 93, Fig. 2, is shown as having contact arm carrying shaft 94 mounted in bracket 95. Mounted on this shaft 94 are contact arms 96 normally yieldably directed toward the contacts 45, 46, by springs 97. The shaft 41 has arms 98 staggered with arms 99 on shaft 43 to carry therebetween the flexible disk coupling 42. Mounted on this shaft 43 is the cam 44. The actuating regions for each direction of oscillation or rocking of the shaft 43 have uniform accelerating portion 100 of the cam 44, one for each direction, each terminating in a less rapid accelerating portion 101. These portions 100 of the cam 44 approximate about 5° inward direction from the tangent of contact of the roller 102 to be actuated by this cam 44. This roller 102 is carried by arm 103 fast with the shaft 94 effective for simultaneous throwing of arms 96 on the shaft 94. This arm 103 has extension 104 (Fig. 6) which in position of rest for the cam 44 is adjacent projection 105 of the cam 44. The cam 44 is accordingly effective for holding the arms 96 outward so that contacts 45, 46, are maintained open until the cam 44 is rocked.
- In rocking the shaft 43, counterclockwise from the position shown in Fig. 6, the roller 102 rides upward approximately 55° upon the slow-up portion 101 effecting a throwing in of the arms 96 rapidly at first and then more slowly later on. As this throw is being effected by the travel of the arm 103, the projection 104 moves into recess 106 of the cam 44. Should the operation of the torque motor 35 be in the opposite direction, similar throw of the arms 96 is effected with the projection 104 riding into recess 107 of the cam 44.
- Driven by the motor shaft 41 of the torque motor 35 is arm 108 integral with coupling arm 99 carrying offset 109. The driven shaft 43 adjacent the coupling 42 is mounted in bracket 110 having bearing 111 (Fig. 5) for the shaft 94 and bearing 112 for the shaft 43. This bracket 110 also carries below the bearing 112 an abutment or stop 113. Loosely mounted upon the projecting portion of this shaft 43 towards the coupling 42 are weights 114, 115, designed as rights and

lefts. Each weight has a depending sound deadening felt pad 116 in a depending ear thereof. The weight 115 has a projection 117 for impacting with felt pad 118 in a recess in the opposing weight 114.

As the torque motor 35 is energized the arm 108, say in clockwise rotation from the motor moves to engage the pad 116 of the weight 114 in the commencement of rotation, throwing such weight 114 so that the felt seat 118 seats against the projection 117. The extent of rocking of the shaft 43 is limited by this weight 115 being held by the stop 113. This throw is adjusted to approximate 55° in either direction. The load of the weight upon the shaft 43 is greater at starting and diminishes as the center of gravity is brought over the shaft 43. Accordingly, this resisting means of the weight 115 or 114 grows less, while the resistance of the springs 97 at the arms 96 may remain approximately constant, but are not effective until there is contact and movement thereafter.

At once the motor 35 is deenergized the springs 97 tend to throw the arms 96 clear of the contacts 45, 46. This recovery is assisted by the weights 115 or 114, rocking the shaft section 41, now not influenced by electromagnetic energy, back to its starting position as determined by the weights 114, 115, bringing the arm 108, 109, into registry with and clear of the stop 113 which stop receives the concussion impact.

The direction switch motor shaft section 53 is connected to cam shaft section 55 in a similar way as to coupling and weights with arm as the shaft section 41 is connected to the cam shaft section 43 at the main switch motor 35. The cams 56, 57, each have the uniform accelerating region 100 (Fig. 8) approximating about 5° away from the tangent for the rollers 102 and terminate in less active portions 101. As to these portions for action the cams 56, 57, are rights and lefts. However, the stop portions to be engaged by the arm 104 are somewhat differently disposed. The cam 56 has stop portion 119 extending in the same semi-circular region as its active cam portion, while the cam 57 has its stop engaging portion 120 extending in the same semi-circular region as the active portion of this cam 57.

While in the operation of this device a one-direction throw cam similar to 56 or 57 might be used in connection with the main switch motor 35, such would thereby prove a phase reversal stop device for the apparatus, precluding any throwing in of the switch motor 35 upon the reversal of phases. However, with the two-direction throw cam 44 adapted to this main motor 35, there is an automatic provision caring for phase reversal in that should supply lines 8, 9, 10, as installed have the phases for operating

the main switch 35 clockwise for up direction travel of the elevator car 3, the rotation of the direction switch motor 5 also clockwise there would be throwing of the cam 57 for actuating the contacts 121, 122. 70 On the reversal of phase this motor 35 would operate counterclockwise and likewise on the same condition for starting, still throwing the controller 21 would operate the direction switch motor 51 counterclockwise, thereby throwing contacts 58, 59. This means that the indication at the controller 21 in the car is good for the phase reversal because the reversal in the lines and one motor means a double reversal, thereby neutralizing the effect for car travel direction indication of the controller 21. It is true that with this reversal, contacts 58, 59, now mean upward travel as against former meaning of downward travel. This is a feature 85 of automatic safety incorporated in this apparatus due to the motor operation of the switches, the motors 35, 51, being polyphase and of the torque type. Furthermore, these motors 35, 51, at once there is a failure on 90 any phase, lose their torque and the springs 97 are at once effective in conjunction with the weights 114, 115, in bringing the motors and likewise the switch contacts into open or initial positions. Accordingly these 95 motors 35, 51, 73, because carrying energizing current when in thrown position, have this safety feature notwithstanding there is a phase line through each of the motors when but one phase is disturbed. In rendering possible this control of polyphase switch control devices remotely from the controller 21 in the car, the controller 21 in the car is connected to more than one phase 100 of the supply lines. 105

The automatic operation for self centering in off position is also true as to the accelerating motor 73 so pulled by the weight 84 dash-pot piston. The three switch controlling polyphase motors 35, 51, 73, may 110 automatically return to off position. This return by these motors to off position may be on failure of one of the phases of the supply. Such return occurs from a non-sealing position. As the accelerator motor 115 cams 79, 80, 81, are bilateral, phase reversing motor 73 does not disturb the net result of the accelerating switch control. Each of these switch operating motors is dissociated from the power motor line as controlled by 120 its switches. These motors are in addition to the power motor of the translation circuit. Furthermore, there is, due to this energizing action of the rotating field in the torque motor, constant pull action by the motor 125 itself so long as the energizing current is therein.

There is symmetry as to the actuators 35, 51, 73. There is symmetry as to the arms 96. Accordingly there is possible inter- 130

change of arms and auxiliary motors, one of each capable for replacement anywhere on the board.

The design of the cams has developed a proper timing for quiet and quick control operation by the remote control herein disclosed.

The extensions 104 of the arms 103 not only coat against throwing in of one switch arm before the cam is in position to hold such arm out but such extensions 104 are effective on rotation of the cam back to off position for positively withdrawing the switch arm from contact or throwing in position. Accordingly in any quick reversal of operation of the torque motor, there is an insured positive pulling out of the switch arm. The throw of the arms 96 as to the travel of such arms largely occurs as the rollers 102 ride along the cam regions 100. The slowing up of the travel of the roller 102 by riding upon the cam portion 101 not only quiets the final closing in action of the arm 96 at the engaging position of the contact in the quick throwing in switches, but this slowing up of travel of the cam allows the motor to more readily compress the spring 97; as the period of motor travel or driving is beyond the throwing in of the switch. There is accordingly a compressing of the spring 97 for holding the contact of the switch against vibration. This compression of the spring operates as a safety device in kicking off for throwing the arm away from switch closing position and is of such effectiveness that even without the weights 114, 115, the arms may be released.

What is claimed and it is desired to secure by Letters Patent is:

1. A switch for power apparatus, said switch being provided with a movable arm, a cam for shifting the arm, a spring yieldably coating between the cam and the arm, and, independent of said power apparatus, a switch motor for actuating the cam, there being means, in addition to the spring, for decreasing the load on the motor as the cam in its travel brings the arm toward fully thrown position to stall the motor with current still energizing said motor.

2. A switch provided with a movable arm and a cam for shifting the arm embodying a uniform accelerating portion, a slowing up portion, and a stop portion as the cam in its travel brings the arm toward fully thrown position.

3. A switch provided with a movable arm and a rotary cam for shifting the arm embodying a first actuating portion of less than tangent from the starting point radial increase, a second slowing up portion, and a stop portion as the cam in its travel brings the arm to fully thrown position.

4. A pair of switches for the translation

circuit of a power motor apparatus, said switches each having a movable arm, an actuating shaft, a switch motor in a control circuit complete in itself independently of said translation circuit, said motor being for actuating said switches from said shaft, and a cam for each switch mounted on said shaft, each cam provided with an arm shifting portion and an arm holding portion oppositely disposed, whereby the shaft in rotation in one direction throws one switch in and holds the other out and in rotation in the opposite direction holds the one switch out and throws the other in.

5. A sectional switch operating shaft embodying a driving section having an actuating arm operable in either direction of rotation, a switch motor for actuating said driving section and a driven section having maintained transmission connection with said driving section and having one weighted arm to be engaged and then lifted in one direction of driving section rotation, and another weighted arm to be engaged and then lifted in the other direction of driving section rotation, a pair of switches having parallel arms, and means on the shaft driven section for throwing the arms of one switch in one direction of rotation and for throwing the arms of the other switch in the other direction of rotation.

6. A switch operating sectional shaft embodying a driving section having an actuating arm effective in either direction of rotation from a position of rest, a switch motor for actuating said driving section, a driven shaft section aligned with the driving section, and having maintained transmission connection with said driving section and having a pair of weighted arms loosely mounted on said driven section, a bracket for the driven shaft section providing an abutment adjacent the position of rest of said actuating arm, said weighted arms normally resting against the abutment clear of said actuating arm, said driving shaft as movable in one direction shiftable freely then to abut one of said arms to lift such arm in one direction of driving shaft travel and to move and then lift the other arm in the other direction of driving shaft travel.

7. A rock shaft having a driving section, a driven section aligned with said driving section, a flexible maintained transmission connection therebetween, a bracket for the driven section providing a stop, an arm fixed with the driving section and registering with said stop, and spaced weights on the driven section normally hanging against the stop, said arm effective in one direction of rotation to move into contact with and then lift one of said weights against the other weight in such one direction of rotation to have such direction of shaft rotation

stopped by the latter weight being held by the stop, and said arm effective in the opposite direction of rotation to move into contact with and then lift the other of said weights to bring it against the one weight to have such latter direction of shaft rotation stopped by the one weight held by the stop.

8. A switch for power apparatus, said switch being provided with a movable arm having a first contact, a second contact to be engaged by the arm contact, a cam for shifting the arm, independent of said power apparatus—a switch motor for actuating the cam, and a spring coacting for follow-up action after said contacts are in abutting relation, there being means in addition to the spring for decreasing the load on the motor as the cam in its travel brings the arm toward fully thrown position to stall the motor with current still energizing said motor.

9. Power actuation means for a switch including a rock shaft driving section, a maintained transmission driven section therefor, a momentum storing weight loosely rockably mounted on the shaft driven section, engaging means for angularly shifting the weight on shaft actuation, and sound deadening stop means for the weight.

10. A switch for power motor apparatus, a switch motor dissociated from the line controlled by the switch, said motor being for actuating the switch for a period of travel beyond the throwing in of the switch, and intermediate transmission change speed means between the switch motor and switch slowing up action at the switch in the final switch closing for quieting switch operation.

11. A switch for power motor apparatus, a switch motor independent of said apparatus for actuating the switch for a period of travel beyond the throwing in of the switch and to a stalled stop position for the switch motor with current still energizing said motor, and intermediate transmission change speed means between the switch motor and switch including a cam slowing up action at the switch in the final switch closing for quieting switch operation.

12. A switch for power motor apparatus, a switch motor independent of said apparatus for actuating the switch for a period of travel beyond the throwing in of the switch and to a stalled stop position for the

switch motor with current still energizing said motor, intermediate transmission change speed means between the motor and switch including a cam slowing up action at the switch in the final switch closing for quieting switch operation, and a spring opposing motor driving during slowing up action of the cam.

13. A switch for power motor apparatus, a switch motor independent of said apparatus for actuating the switch for a period of travel beyond the throwing in of the switch and to a stalled stop position for the switch motor with current still energizing said motor, a member directly connected and positively driven by the motor, and an arm for throwing the switch, said member being movable relatively to the arm and having means coacting to move the arm positively into and out of switch closing position.

14. A switch for power motor apparatus, a switch motor independently of said apparatus, a member positively driven by the motor, a two-part arm as to which the member is relatively movable, each part having a guide, a shaft providing a common axis for said two-part arms, an adjustable bolt through said guide, and a compression spring on said bolt for abutting one arm and through the bolt effective for holding the other arm toward said member, said two-part arm being operable for throwing the switch as actuated by the member.

15. A switch for power motor apparatus, a switch motor dissociated from the line controlled by the switch, said motor being for actuating the switch for a period of travel beyond the throwing in of the switch, and intermediate transmission change speed means between the switch motor and switch slowing up action at the switch in the final switch closing for quieting switch operation, said transmission means being provided with a movable lock out for the switch in opened position for the switch as determined by said means.

16. A switch having a movable arm, a motor having a shaft for shifting said arm to switch closing position, and means precluding operating said arm to switch closing position independently of operating said shaft.

In witness whereof I affix my signature.

ERNEST B. THURSTON.
